UNITED STATES PATENT OFFICE.

JOHN JOHNSTON, OF LONDON, ENGLAND, ASSIGNOR TO ARCHIBALD EDWARD DOBBS, OF LONDON, ENGLAND.

HYDROCARBON-VAPOR BURNER.

SPECIFICATION forming part of Letters Patent No. 703,591, dated July 1, 1902.

Application filed February 18, 1902. Serial No. 94,583. (No model.)

To all whom it may concern:

Be it known that I, JOHN JOHNSTON, a subject of the King of Great Britain and Ireland, residing at No. 19 Park road, New Cross, in 5 the county of Kent, England, have invented certain new and useful Improvements in Hydrocarbon-Vapor Burners, of which the following is a specification.

My invention has relation to a burner for 10 consuming liquid fuel, such as hydrocarbons, and in such connection it relates to the construction and arrangement of the parts constituting such a burner.

The principal object of my invention is to 15 provide a burner for hydrocarbon or similar liquid fuel in which a large body of flame can be produced and in which the volume or body of the flame can be regulated to suit varying conditions of work.

20 My invention consists, first, in so disposing the burner proper within a surrounding deflector that a vertical adjustment of the burner within the deflector simultaneously varies the amount of exposure of the flame 25 of the burner with regard to the deflector and the opening controlling the supply of vapor or fuel to the burner, and, second, in making the surrounding deflector in such a construction hollow and a part of the vaporizing apparatus for the burner.

The nature and scope of my invention will be more fully understood from the following description, taken in connection with the accompanying drawings, in which—

35 Figure 1 is a vertical sectional view of a burner embodying main features of my invention. Fig. 2 is a horizontal sectional view taken on the line 2 2 of Fig. 1, and Fig. 3 is a side elevational view of the burner.

40 In the drawings the burner is illustrated as adapted to be supplied with petroleum or similar hydrocarbon fuels and to be used in the generation of steam in a motor-car; but such special use is not the only use to which 45 the burner may be put without departing from the spirit of my invention.

Referring to the drawings, *a* represents a vaporizing-chamber mounted upon the upper end of a casing *b*. The interior *d* of the 50 chamber *a* is preferably annular and in cross-section is triangular, having an inner inclined

or conical face *g*. Within the casing *b* and surrounded by the vaporizing-chamber *a* is arranged the circular burner *c*. The fuel is supplied by a pipe *d'* to the interior *d* of the 55 vaporizer *a* and flows in a circuitous path through the same and into a coil or ring *e*, situated above the vaporizer *a* and burner *c*. The vapor from the coil or ring *e* is fed to a burner-nozzle *f* at the lower part or base of 60 the casing *b*. The circular burner *c* has a series of outlet-jets projecting toward the conical deflecting-face *g* of the vaporizer, so that the flame from the burner may strike said deflecting-face *g*. The burner *c* is so arranged 65 that it may be moved up or down within the deflecting-face *g*, so that its jets may be more or less covered by said face *g*, according to the movement of the burner *c*. The burner *c* is preferably made in the form of a circular 70 chamber having a central hollow spindle *h*, constituting the induction and mixing chamber for the burner. The vapor from the nozzle *f* passes upward in the spindle *h*, and in its passage air is sucked with it through the 75 open lower end of the spindle *h*. The spindle *h* of the burner is arranged to slide up and down in a boss formed by the casing *b*, and this movement of the spindle *h* is preferably secured by the following means: Upon the 80 hollow stem or spindle *h* are formed the projections or pins *j*, adapted to be engaged by the forked ends of a bell-crank or other lever *i*, pivoted in the casing. From the base of the 85 annular head of the burner *c* projects a flange *k*, which works up and down in a guide-ring *l*, formed by the casing *b*. A shoulder *m* at the base of the annular chamber of the burner *c* rests upon the ring *l* when the burner *c* is in its lowermost position. Through the hollow 90 spindle or stem *h* of the burner is passed a needle-like cone *n*, which enters into the vapor-nozzle *f* to close or regulate the flow through said nozzle *f* into the spindle *h*. The needle-cone *n* is supported by and travels 95 with the burner *c*, so that a movement up or down of said burner *c* will cause the cone *n* to retract from or enter more tightly in the vapor-nozzle *f*.

In the operation of the burner if the stem 100 or spindle *h*, with the annular head of the burner, be raised the jets from the burner

will clear, more or less, the deflector-chamber *d*, and a larger volume of flame issuing from the burner will result. At the same time the lifting of the annular burner-head will 5 raise the cone *n* from the vapor-nozzle, and hence a larger supply of vapor and air will enter the spindle and burner-head, causing more flame and more heat to issue from the burner.

10 The vaporizer *a* is connected conveniently to the guide-ring *l* of the casing *b* by means of studs *o* or the like, which permit the vaporizer to be removed from the casing, if desired, and also isolate or separate the vaporizer from said casing. The nozzle *f* is preferably formed upon a bracket or branch pipe *p*, supported by the casing *b*, and the bracket or pipe *b* is coupled directly to the outlet-pipe of the coil *e*. Under the annular vaporizing-chamber *d* is mounted a dish or other receptacle *q*, into which methylated spirits or the like may be introduced and burned at the initial starting of the vaporizer. At the lower end of the casing *b* and below the outlet from the nozzle *f* is arranged a drip-trough *t*, having an outlet-pipe *r* for delivering the waste accumulating beneath the stem of the burner. The annular head *c* of the burner and the supporting hollow spindle *h* thereof 25 are separated by circular openings or holes *s*, through which air may pass to the center of the flame, thus causing the flame to issue from the burner as a ring-like body with a hollow center or core.

30 Having thus described the nature and object of my invention, what I claim as new, and desire to secure by Letters Patent, is—

1. In a hydrocarbon or similar burner, an annular burner-head, a stationary annular 35 vaporizing-chamber surrounding the burner-head, the face of said chamber adjacent to the burner-head being arranged to deflect the flame from said burner-head, a vapor-nozzle located below the burner-head, a needle-cone 40 carried by said burner-head and entering the vapor-nozzle, and means for elevating the burner-head to simultaneously lift the burner- 45 surface above the deflecting-face of the vaporizer and to elevate the needle-cone from the 50 vapor-nozzle.

2. In a hydrocarbon or similar burner, a vapor-nozzle, a needle-valve controlling said nozzle, a burner-head carrying said needle-valve, an inclined deflector-plate surrounding the burner-head, and means for elevating the burner-head to thereby simultaneously elevate the needle-valve and cause the burner-head to clear the deflector-plate. 55

3. A hydrocarbon or similar burner, comprising a movable annular burner-head, a stationary annular vaporizing-chamber surrounding said head and having a flame-deflecting surface on that side adjacent to the burner-head, a vaporizing-coil passing from the chamber in a convolution above the 60 burner-head, a vapor-supply nozzle located below the burner-head and connected with said coil, a hollow stem supporting the burner-head and surrounding the vapor-nozzle, a stationary guide for said stem, a needle-regulator carried by the burner-head and entering and engaging the opening in the vapor-nozzle, and means for imparting vertical 65 movement to the hollow stem, burner-head and needle-regulator. 70

4. A hydrocarbon or similar burner, comprising a movable annular burner-head, a stationary annular vaporizing-chamber surrounding said head and having a flame-deflecting surface adjacent to the burner-head, 80 a vaporizing-coil passing from the chamber in a convolution above the burner-head, a vapor-supply nozzle located below the burner-head and connected with said coil, a hollow stem supporting the burner-head and surrounding the vapor-nozzle, a stationary guide for said stem, a needle-regulator carried by the burner-head and entering and engaging the opening in the vapor-nozzle, means for imparting vertical movement to the hollow 85 stem, burner-head and needle-regulator, and a drip-trough surrounding the base of the vapor-nozzle. 90

In witness whereof I have hereunto set my hand in presence of two witnesses.

JOHN JOHNSTON.
